(57) **CLAIM**

The ornamental design for a combined clock face and pendulum, as shown and described.

DESCRIPTION

FIG. 1 is a front perspective of a combined clock face and pendulum in accordance with the invention;

FIG. 2 is a right side elevation of a combined clock face and pendulum;

FIG. 3 is a left side elevation of a combined clock face and pendulum;

FIG. 4 is a front elevation of a combined clock face and pendulum;

FIG. 5 is a rear elevation of a combined clock face and pendulum;

FIG. 6 is a top plan of a combined clock face and pendulum; and,

FIG. 7 is a bottom plan of a combined clock face and pendulum.

The broken lines in the drawings are for illustrative purposes only and do not form part of the claimed design.
